UNITED STATES PATENT OFFICE.

OSCAR S. FIELD, OF ROSELLE, NEW JERSEY, ASSIGNOR TO THE UNION SWITCH AND SIGNAL COMPANY, OF SWISSVALE, PENNSYLVANIA, A CORPORATION OF PENNSYLVANIA.

AUTOMATIC TRAIN CONTROL.

Application filed December 11, 1923. Serial No. 679,809.

My invention relates to automatic train control systems and apparatus. Such systems are ordinarily designed to supplement the usual block signaling systems and I 5 shall describe my invention as being thus employed although its use is not necessarily thus limited. Train control systems as heretofore designed have some of them been continuous in their control and some of them 10 intermittent, much of the apparatus being interchangeable whichever method is employed. Preferring the continuous method, I have shown my system and apparatus as thus adapted, but many of the novel features thereof could equally be employed in connection with the intermittent type of 15 system.

The most vital function of a train control apparatus is to insure the stoppage of 20 a train in a "caution" zone before it has passed into a "danger" zone. One defect of automatic train control systems as heretofore devised is that they compel unnecessary reduction of speed because of their in- 25 elasticity to adapt themselves to different local conditions, as for example, differences in track grade. The ordinary train control apparatus in practice treats all parts of the track alike in this respect and, therefore, in 30 order to be sure that the brakes shall be applied early enough and with the rapidly required to ensure safety at any section of the road bed, a permissible train speed curve is determined and fixed by the apparatus 35 for the most unfavorable stopping conditions, which will cause an earlier brake application and a more rapid speed reduction than are necessary at most parts of the road. This results in a marked loss in traffic ef- 40 ficiency and constitutes a serious objection to the employment of such train control systems. One object of my invention is the provision of a train control system and apparatus which will be automatically ad- 45 justed as the train moves along the track in such manner as to control in proper accordance with local track conditions, so that in each section of the track the control during "caution" conditions will be of such 50 character as to permit maximum average speeds consistent with safety. To this end my invention involves a construction by which in traveling over a short section of the track, the apparatus may be acted upon

responsively to the currents therein to ad- 55 just the apparatus so that it will determine in the succeeding portion of the track the decelerating curve best suited therefor.

Another feature of my invention involves the provision of train control apparatus 60 adapted to compel speed reduction when approaching portions of the track where speed should always be limited, and to determine and compel maximum relatively low speeds throughout such sections. To this end there 65 is provision whereby the apparatus may be adjusted in response to the track circuits in a section of the track to set up a decelerating curve in a succeeding portion of the track, and after passing over a short length 70 where such deceleration curve governs be in condition to be responsive to track cir- 75 cuits to determine a constant speed.

My invention, independently of its said 80 elastically adjustable features, also involves a train control apparatus and system operating upon novel principles to function efficiently and reliably to effect the generally desired objects of such apparatus, includ- 85 ing the compelling of the application of the brakes whenever danger conditions develop in the track or whenever any part of the train control apparatus is defective. One such principle is that the apparatus is con- 90 structed so that when actively functioning to determine train speeds, it controls the application of the brakes through apparatus governed by the relation between the speed of the train and that of a part of the control apparatus which part is either con- 95 trolled for a gradually reducing speed to determine a deceleration curve or for a constant speed to determine a maximum train speed. Other such principles of construc- 100 tion and operation will appear in the course of the following description of one specific embodiment of my invention.

In the particular embodiment of my in- 105 vention herein set forth, there is a speed limiting motor which normally maintains the automatic brake valve circuit closed (brakes released) if the speed of the train is below the predetermined safe value, but automatically opens the circuit to apply the brakes if the engineer disregards the pre- 110 scribed maximum speed. Where deceleration is required, the motor is controlled for automatic deceleration along the aforesaid

speed limit curve it is to define thereby compelling the engineer, so long as caution continues, to reduce train speed in accordance therewith.

5 It is desired that the deceleration curve defined by the limiting motor should be of variable slope and length depending upon the track grade, etc., and to effect this function I have devised means for varying the 10 decelerating rate of the speed limiting motor which in the present embodiment comprises a second or regulating motor which is partially controlled by the movement of the train. Where these motors are of the electric type, as preferred, this can be effected by a controller inserted in the limiting motor circuit and driven differentially by the two motors, the one tending to actuate the controller to reduce its own speed and 15 the other tending to actuate the controller in the opposite direction. The speed of the regulating motor is determined and automatically varied by a controller in its circuit which when functioned for determining 20 a decelerating curve is directly under the control of and actuated by the train, and the arrangement is such that upon entering a caution block the regulating motor controller is set to a predetermined value corresponding to the distance within which the 25 train may be safely brought to rest, according to the track conditions in that section, and throughout the decelerating period this controller is gradually operated by the movement 30 of the train along the track to bring the regulating motor to zero speed, so that though the controller for the limiting motor is being operated in one direction to cause the latter to automatically slow up, in the 35 present embodiment by driving the controller from the limiting motor itself, the regulating motor tends to modify or oppose this operation of the controller and flatten out the decelerating curve and force the 40 limiting motor to operate throughout the predetermined decelerating distance of the train.

Where it is desired to fix some uniform maximum speed limit, as for example on sharp curves, this apparatus may be employed to compel the engineer to reduce his speed to a value corresponding to a predetermined point of the decelerating curve established by the limiting and regulating 50 motors, and this may be effected by automatically releasing the regulating motor controller from the train drive at the proper point during the decelerating period and holding the same stationary throughout the 55 speed limit section, thereby forcing the two motors to assume a constant speed above which the engineer is not permitted to drive his train; the speed limiting motor, in the manner indicated above, automatically applying the brakes if the engineer should 60 65

disregard the predetermined speed limit conditions.

For a better understanding of my invention, including the novel features above enumerated and others which will herein-after appear, reference may be had to the accompanying drawings forming a part of this specification wherein:

Fig. 1 is a diagrammatic illustration of the construction and circuits of one specific embodiment of my invention.

Fig. 2 is an elevational view of a detail of the system, and

Fig. 3 is a section on the line 3—3 of Fig. 2.

Fig. 4 illustrates a suitable form of construction for the switches 49 and 55 which control the holding and setting magnets and a bypass for the speed contacts.

Fig. 5 is a plan view of the mechanism controlling the movement of the rheostat for motor B;

Fig. 6 is a diagram of a suitable arrangement of track circuits to give track currents suitable for controlling the relay R.

Referring to the drawings, I have indicated diagrammatically an apparatus which is carried by the train and which is capable of effecting the automatic train control above indicated, the drawings being purposely diagrammatic for convenience in exposition.

I have indicated at V an automatic train brake valve of any usual construction, and it is understood that when the valve magnet is energized the brakes are released and the train is under the entire control of the engineer, but if this magnet becomes deenergized for an appreciable time, the brakes are automatically set independently of the control by the engineer. I have also indicated conventionally a three-position relay R, the latter controlling the contacts 10, 11 and 12. The relay R is responsive to the track circuits to effect the opening or closure of these contacts, as for example, whenever two currents are present in the track and have one relative direction or phase, the relay switch is at the left, in which position the contact 10 is closed, and when the relative direction or phase of these currents is reversed, the relay switch is to the right to close contact 11. Similarly when one or both of the currents are absent, as when danger conditions exist, the relay switch occupies a neutral position between the contacts 10 and 11 with the contact 12 closed. With the relay switch in the position indicated in the drawing, namely to the left, and positioned to close the contact 10, it is observed that the brake air valve magnet V is energized to automatically permit the release of the brakes by the engineer through a circuit from the positive side of any suitable source through the relay switch and

contact 10 and the conductor 13 through the brake magnet V to the negative side of the line. This position of the relay is that which the relay will assume when the train 5 is for example, on a clear block where no speed limit is to be imposed and the train control apparatus need not be active. My apparatus includes a speed limiting motor A which automatically maintains the 10 circuit of the brake magnet V closed during its operation and control period, so long as the train speed is maintained relatively at or below the speed of the motor, but if the engineer permits the speed of the train to 15 rise beyond the speed determined by the motor A, then the brakes are automatically applied through the interruption of the brake magnet circuit. Specifically this is effected directly through the medium of a 20 pair of "chaser" contacts indicated generally by the letters C and illustrated more in detail in Fig. 2, one of these contacts being driven by the motor A and the other being driven by the train wheels. I have indicated 25 one of the train wheels at W and geared to this wheel is a suitable drive shaft 14 which drives, through a pair of bevels 15, a counter shaft 16. The latter has mounted thereon a contact carrier 17 which, through the 30 slip clutch mechanism 18 indicated, is capable of relative movement in one direction with reference to the shaft 16, but in the opposite direction the member 17 becomes clutched to the shaft 16. The carrier 17 carries 35 one of the contacts C. The other contact C is disposed rearwardly of the contact C carried by the member 17 and is carried by the carrier 19 mounted on the shaft a of motor A. The carrier 19 is 40 mounted on the shaft of motor A with a slip clutch similar to the ball clutch mechanism 18 interposed between the shaft and the carrier to provide for relative movement in one direction. In the position shown, the 45 contacts C are in engagement, which means that the carrier 19 is being driven by the shaft of motor A at a speed not less than the speed of the shaft 16, but if the train speed or the speed of shaft 16 should rise beyond 50 the speed of the shaft of motor A, then the member 17 would overrun the member 19 and thereby interrupt the brake valve circuit at C, to cause the automatic application 55 of the brakes. This circuit with the relay R in the neutral position leads from the positive side of the source through the conductor 22, contacts C, conductor 23, conductor 13, and through the valve magnet to the negative side of the source, it being 60 observed that the contacts C are in multiple with the relay contact 10. Driving pins 21 are provided respectively on the carriers 17 and 19 for engagement with each other when the carrier 17 overruns the shaft a and drives the carrier 19.

By causing the motor A to gradually slow up in speed from high, a speed limit deceleration curve may be defined which will compel the engineer to reduce the train speed in accordance therewith on penalty of brake 70 application through the interruption of the brake circuit at C, assuming previous interruption at contact 10. This deceleration of motor A may be effected through a controller which is actuated in any suitable manner to 75 gradually slow it up, but in the present embodiment this controller is automatically responsive to its own movement. The controller must be adapted to the particular type of motor employed, motor A being illustrated 80 as of the direct current electric type in the modification illustrated and adapted to be controlled by a rheostatic or resistance controller 28. When the relay is at neutral motor A has a circuit as follows: from the positive terminal of a source of current, conductor 25, motor A, conductor 26, collector ring 27, controller 28, conductors 29 and 31, relay contact 12 conductor 32, switch contact 33 (closed as described below), and conductor 34 to the negative side of the source of current. Preferably the deceleration is modified by the track or grade conditions, and to this end I have devised means for 85 varying the deceleration curve of the motor A according to the requirements of the particular section of track where the train is to be decelerated. The controller 28 is actuated to gradually slow up the motor A when the latter is operating, as for example by 90 being directly driven therefrom, but for the purpose indicated of modifying the deceleration curve of the motor A, a motor B is provided which tends while it is operating to 95 actuate or modify the action of the controller 28 to speed up motor A, the two motors therefore operating differentially upon the controller 28. For this purpose the controller 28 is geared as indicated diagrammatically to the differential 100 between the shafts of motors A and B. When the relay is at neutral motor B has a circuit as follows: positive side of the source, conductor 36, motor B, conductor 37, collector ring 38, controller 39, conductors 40 and 31, relay contact 12, conductor 32, switch 33 (closed as described below) and conductor 34 to the negative side of the line. The controller (rheostatic) 39 is controlled independently of the 105 motors A and B. 110

In the position indicated the motors are at rest with all resistance of controller 39 in circuit and all resistance of controller 28 out of circuit, and their external circuits are open. The controller 39 during the decelerating 115 period of the train, is adapted to be driven directly from a train axle as for example from the shaft 14, the direction of rotation of controller 39 being such as to gradually slow up the motor B. The method of drive is in 120 125 130

dicated more or less diagrammatically, as for example by a gear 41 driven by the upper end of the shaft 14, which gear 41 in turn drives the reversing gears 42 and 43, the latter being mounted on a carrier 44 which is pivoted to the axis of the gear 41, the arrangement being such that when the gear 42 is brought into engagement with the gear 45 of the controller 39, the latter is automatically driven to cut out its resistance, while when the other gear 43 is in mesh with 45, the controller is rotated in the direction to gradually cut in its resistance and slow up the motor B. The ratio between gear 42 and gear 45 is desirably made smaller than the ratio of gear 43 and gear 45, thereby cutting resistance out at a greater speed than it is cut in to ensure a relatively short set up section. This is effected through a small gear 42' which meshes with 41 and is fixed to larger gear 42. The gear 45 is provided with the gap 45' which causes the automatic arrest of the movement of the controller 39 when the gear 43 reaches the gap. In the normal or rest position of the apparatus the free or overhanging end 46 of the carrier 44 drops down by gravity and automatically carries the gear 43 into a position to mesh with the gear 45.

An electro-magnet S, when energized, lifts the armature 47 carried by the overhanging end 46 and effects the meshing of the gear 42 with the gear 45. This magnet S is energized when the relay R is in the right hand position through a circuit as follows: from the positive side of the line, contact 11, conductor 48, switch 49 (when in position indicated in Fig. 1), conductor 50, and thence through the coil to the negative side of the line. For a purpose hereinafter specified, the armature 47 carries a switch 51 which bridges or short-circuits the "chaser" contacts C.

The operation of the apparatus thus far described whereby it may be set up or adjusted for a decelerating curve suited to a particular section of track is as follows: The relay moves to the right in response to the currents in the track and it is only necessary that the track circuits in a selected short length of track be in the proper relative direction to maintain the relay at the right while the train travels a definite distance. The apparatus is set-up by moving the relay from left to right and maintaining it at that position until the desired adjustment is secured. Such a section is hereinafter referred to as a set-up section. The circuit of the brake valve magnet which maintains the brakes released is normally closed through the left hand contact 10 of the relay, but when a set-up section for deceleration in a caution block is entered and the relay moves to the right it closes the contact 11, thereby energizing the electro-magnet S through the conductor 48, switch 49 and conductor 50, and the brake circuit is now closed through the conductor 22, switch 51, and conductor 23. The air brake valve is purposely designed with a certain degree of sluggishness in action so as not to apply the brakes during the transition period of the relay in going from the contact 10 to the contact 11. The energization of the magnet S throws the gear 42 into mesh with 45 to drive the motor B controller 39 and the resistance thereof is automatically cut out by the train axle to an extent determined by the length of the set-up section preceding the beginning of the decelerating period, this section being of a predetermined length based upon the conditions of the track or grade. For example, a down grade requires a longer distance within which to bring the train to a standstill than the more favorable up grade, and hence the former requires a longer set-up section. Upon leaving the set-up section and entering the decelerating portion of the caution block, the relay R is no longer under the influence of the two currents of the set-up section and moves to the middle or neutral position to close the circuits of both motors A and B at switch 12, the switch 33 having been closed at the initial movement of rheostat 39 from the position indicated in the drawing. The motor B having a portion of its controller resistance removed during the passage through the set-up section of the track, begins to operate and through the planetary or differential gearing 35 opposes the cutting in of the controller 28. Motor A starts with all its resistance initially out of circuit and is at a speed above that of the train to close the brake valve circuit at the contacts C before the air valve can act to set the brakes abruptly. Simultaneously with the relay going to the neutral position from the contact 11, the electro-magnet S is deenergized and the train axle is now geared to the motor B controller 39 to return it to its normal position of high resistance, and this permits the motor A to insert its own resistance and reduce its speed along a decelerating curve modified by the differential action of the motor B operating in opposition thereto. At the end of the deceleration section both motors come to rest, the controller 39 and switch 33 being in the position illustrated. A switch 58 forms an independent circuit for motors A and B and is open only in the one position where the resistance of controller 28 is all cut out so that the apparatus comes to rest in the proper position for starting at the beginning of a set up section. Throughout the decelerating period, the engineer must reduce the train speed to keep it below that of the decelerating curve of motor A, otherwise the brakes will be applied automatically by interruption of the brake contacts at C. It

- is thus apparent that the deceleration of the motor A and accordingly the deceleration of the train may be predetermined in accordance with the track or grade conditions
- 5 at the particular point concerned to give either a long flat decelerating curve or a shorter steep one, the efficiency of the train operation being thereby maintained at a maximum at all times. By track or grade conditions, it is understood that I mean any local operating conditions which affect the safe decelerating and running speeds of the train, such for example, as curves, grades and defective road beds.
- 10 Variations of speed or even stoppage of the train, as long as the speed of the train is below that permitted by the control apparatus does not notably or at all harmfully affect the deceleration curve enforced by the apparatus because the cutting in of the resistance of the rheostat of motor B is correspondingly varied or stopped, and the actual speed of motor A at any moment is (because of the slip clutches) independent
- 15 of the speed of the train, a condition that is desirable where motor A is controlled differentially by itself and motor B. Where the adjustability of the deceleration curve by providing regulating motor B and its adjustment by track currents are not desired, then the slip clutch 18 between the carrier 17 and train drive 16 is not added because the variations of speed of the train below the permitted speeds and even the stoppage of
- 20 the train are compensated for by corresponding variations of actual speed and by stoppage of motor A as contrasted with the speeds at which its controller tends to cause it to run.
- 25 If a danger condition should suddenly arise at any time the track currents, or one of them, are short-circuited or cutoff from the train and relay R goes to neutral, being biased by gravity thereto in the usual manner of train control systems. Under these
- 30 conditions the train brakes are applied and the train brought to rest, under the control of motor A if the latter happens to be functioning when the danger condition arises and independently thereof if the motor A is at rest when the danger condition arises, the coil V being deenergized at the contacts C whenever the carrier 18 overruns the carrier 19.
- 35 The system or apparatus above described for predetermining the train deceleration depending upon the road bed conditions, may be also used to determine any constant speed limit for the train on a particular section or sections of the track, as for example when going around curves. This may be effected generally by setting up for a deceleration period as above described and then at a particular point of the deceleration curve corresponding to the speed which it
- is desired to maintain, means are provided for disengaging the controller 39 altogether from the train axle, thereby bringing it (the controller 39) to rest and fixing the speed of the motor B at a constant value to cause
- 40 both motors A and B to continue to operate. This is effected through an electro-magnet H operating on an armature 52 which is pivoted on the pivotal axis of the carrier 44 and engages a pin 54 on the member 46, thereby
- 45 lifting the member 46 sufficiently to prevent the lower gear 43 from engaging the gear 45 but at the same time not high enough to bring the gear 42 into engagement with it. The pin 54 is indicated as passing through
- 50 a slot in the arm of armature 52. The electro-magnet H is energized through the contact 11, the conductor 48, the switch 49 and the conductor 53, the switch 49 having been thrown to the left by the controller 39 when
- 55 it has reached the end of the set-up section preceding the constant speed section.
- 60 In the particular embodiment illustrated, the set-up section preceding a constant speed section is longer than the longest of the usual
- 65 set-up section preceding a danger or caution block, so that the switch 49 is never thrown to the left during the usual set-up section for caution, but is thrown to the left at the end of the set-up section preceding a constant speed limit section. For example, the controller resistance 39 is devised of sufficient length so that only a portion
- 70 thereof is cut out during the longest usual set-up period, but for a set-up period preceding the constant speed section a greater portion or, if desired, all of the resistance is cut out, causing the motor B to start at a maximum speed at the beginning of the decelerating period. A pin 49' is driven from
- 75 the controller 39 and adapted as shown in dotted lines to throw switch 49 to the left at the end of the set-up section and to throw it to the right again at the end of the backward movement of the controller. In order
- 80 that the length of set-up block and the apparatus need not be too finely adjusted, I have provided a switch 55 which is also closed simultaneously with the throwing of
- 85 the switch 49 to the left, the switch 55 being connected through the conductors 56 and 57 across the "chaser" contacts C and thereby maintaining the brake valve circuit closed as long as the relay R remains to the right
- 90 and until the motors start. The switch 55 is opened again immediately the controller becomes geared to the train axle and begins its return movement at the end of the set-up section. At the beginning of the deceleration period the relay goes to neutral
- 95 and closes the contact 12, thereby deenergizing both magnets S and H and permitting the motors A and B to be brought up to speed and then begin their decelerating control in the usual manner. At the par-

65 ticular point on the deceleration curve desired, the track circuits being again such as to cause the relay R to assume the right hand position, the holding coil H is energized, which releases the rheostatic controller 39 from the train drive and causes the motor B to run at a constant speed thereby also maintaining the controller 28 through the differential connection at a substantially 10 stationary position, both motors A and B continuing to operate at constant speed. When the relay R goes to the right to break the motor A and B circuits at the contact 12, provision is made for the maintenance of these circuits through a switch 58 which is adapted to be closed at all positions of the rheostatic controller 28 except with the resistance all out. At the end of the constant speed section the track circuits 15 are such as to cause the relay R to go to the left to a clear position, thereby energizing the brake magnet V independently of the "chaser" contacts C, and since both coils H and S are now deenergized the carrier arm 20 46 operates by gravity to bring the gear 43 into mesh with the controller 39, thereby bringing both motors A and B to rest at their zero or initial positions. If at any 25 moment while passing through the constant speed section a danger condition should develop, indicated by bringing the relay R to the neutral position, the circuit of the holding magnet H would be opened and motor B controller would again become geared to the train axle so that the usual decelerating 30 curve, long and flat in this case, would be set up. The constant speed condition may run through several blocks.

40 It will be observed from the foregoing that whenever the relay is at the left, the train control apparatus is at rest. Whenever, however, the relay is at its neutral or gravity position, the train control apparatus is functioning to compel deceleration of the 45 train. If the relay has gone to neutral following a period at which it has been at the right, then the apparatus is functioning to compel a deceleration within a predetermined curve for which the apparatus has 50 been set up. If the relay has passed to neutral after being maintained at the left, then the motors will be at rest and the brake will be applied promptly, if the train is moving 55 at all. If the relay moves directly from the left to the right, then while it is maintained at the right the apparatus is being set up for later control of speed, but is inactive at the moment to limit speed. If, however, the 60 relay moved to the right from its neutral position after a period of deceleration and the apparatus has previously been set up to close the circuit of the holding magnet H, the apparatus functions to enforce a constant, predetermined speed limit. These 65 various operations of the apparatus, as gov-

erned by the movements of the relay, adapt the apparatus to be controlled to meet all conditions along the track merely by providing well known means such as apparatus including means responsive to the inductive effects of track circuits and means for amplifying the induced currents to make the relay responsive to the track circuits, and equally well known means for controlling sections of the track so that at certain sections and under the proper traffic conditions there will be two currents of such relative direction or phase as to bring the relay to the left. In certain short sections of predetermined lengths the track currents shall, 70 when the traffic conditions call for the setting up of the apparatus, be in a relative direction or phase to move the relay to the right and in certain other short but relatively longer sections the current shall like- 75 wise be arranged so that under suitable traffic conditions the relay shall be at the right for a long enough period to operate the switch controlling the holding magnet, 80 such sections being followed by a section 85 where at least one track current shall be absent, the length of such section being such as to impose a desired constant speed when the train passes to a portion of the track 90 having currents which will again bring the 95 relay to the right.

100 While I have described the constant speed limit which the apparatus may compel as being one lower than the maximum speed at which the train is operating on a clear straight track, yet the apparatus may be controlled to enforce maximum speed limits at all parts of the track, the apparatus being as readily designable to be set up for the maximum speed permissible anywhere on 105 the road as for any lower speed.

110 Referring now to Fig. 6 which illustrates suitable track circuits for operating the relay R, I have shown two block sections and short portions of two additional block sections, the rails 70 and 71 of the track being divided into sections by insulation 72 in the usual manner. Primaries 73 of 115 transformers receive alternating current from any suitable source and each primary cooperates with four secondaries 74, 75, 76 and 77. The secondary 77 supplies current to a coil 78 of a track relay TR which has a second coil 79 connected across the track. Whether or not this is the same track relay 120 as controls the usual block signals or a separate one, is of no consequence. The secondary 76 supplies current through the switch arms 80 and 81 of the track relay to the track, being connected to the opposite rails at the exit end of the block section. 82 is a reactor in this circuit to adjust the phase of the current therein. When no train is in the block 125 current from secondary 76 passes through the block to the coil 79 of the track relay 130

at the entrance end of the block and causes the relay to move its switch arms to the left or right according to the relative direction of the current thus brought through the 5 track to coil 79. The relative direction of this current is controlled by the position of the switch arms 80 and 81 at the exit end of the block, the current being in one relative direction when the switch arms are either at the 10 left or at the right, and at the relatively opposite direction when the switch arms are in a vertical position due to deenergization of the track relay coil 79.

The secondary 75 supplies a circuit 15 through the switch arm 92 of the adjacent track relay, which circuit includes the rail 71 from the entrance end of the section to a point a predetermined distance (the set-up distance) from the exit end thereof. There 20 is a non-inductive resistance 83 in this circuit to adjust the phase of current therein. When the switch arm 92 is either at the right or at the left the circuit of secondary 75 is a closed circuit through the greater 25 part of the rail 71 of the block section, but when the switch arm 92 is at the neutral position this circuit is open.

The circuit of secondary 74 is permanently connected across a short length of the rail 30 71 near the exit end of the block, this length of rail being that which determines the setting up of the apparatus. A non-inductive resistance 84 is placed in this circuit.

In one of the block sections I have shown 35 the front wheels of a locomotive 85, an inductor 86 forward of these wheels and in inductive relation with the rail 70 and an inductor 87 rearward of these wheels and in inductive relation with the rail 71. The coil 40 of the inductor 86 applies current to the winding 88 of relay R and the coils of inductor 87 supply current to the winding 89 of relay R.

When the train is in a clear block section, 45 that is when the block ahead is clear, the coil 88 of the relay R is receiving current by induction from the circuit of secondary 76 while coil 89 of the same relay is receiving current by induction either from 50 the secondary 75 or the secondary 74 according to the position of the train in the block.

As the block ahead is clear, the switch arms 80 and 81 are either at the right or 55 at the left so that the current from secondary 76 is in the relative direction with respect to the current from secondary 75 to react to move the switch arms of the relay R to the left. As soon, however, as inductor 87 approaches near enough to the exit end of the block section to be influenced 60 by the current from secondary 74 then the switch arms of the relay R shift to the right because the currents in the track rail 71 65 from secondaries 74 and 75 are in relatively

opposite directions. Thus, when the train is about to leave a section approaching an unoccupied block, the setting up described in the specification is effected, the amount of setting up being dependent upon the 70 length of track during which inductors 86, 87 are simultaneously in inductive relation with that part of the track in which current from secondary 74 is circulated.

If, however, the train is in a section approaching one that is occupied, that is, if the train has entered a caution block, then there will be no current in the rail 71 from secondary 75 because it will be interrupted at switch arm 92 and, therefore, as the train 75 passes through the block the switch arms of 80 relay R will be at the neutral position so that the permissible speed apparatus will be in full operation. It is not desirable that the set up apparatus should be operated in 85 a caution block and, therefore, when the train reaches the set up section of the caution block the switch arms of the relay R will be at the left because the switch arms 80 and 81 of the track relay in the block 90 ahead are at the neutral position, thus reversing the relative direction of the current from the secondary 76.

While I have illustrated one specific form 95 of track circuits and arrangement of inductors, these form no part of the invention herein described and claimed.

I claim:

1. In train control apparatus of the type 100 employing means for causing a permissible train deceleration, regulating devices for controlling the rate of such permissible deceleration from a given maximum permissible speed, a controlling circuit for such 105 devices and means adapted to be responsive to currents along the track for regulating said circuit to correspondingly vary the action of said regulating devices.

2. A train control device, a circuit directly controlling the same, another circuit and 110 speed control apparatus therein controlling said device, a regulator for the speed control apparatus, means for setting up the regulator to adjust its regulating effect, a third circuit including said setting up 115 means, and apparatus adapted to be responsive to currents along the track to complete any one of the said three circuits.

3. In train control apparatus, means for 120 determining permissible train deceleration, including a movable member whose initial position determines the rate of deceleration from a given maximum permissible speed, and means for causing the train by its movement through any selected distance to 125 correspondingly move said member to fix its initial position.

4. In a train control system, permissible 130 train deceleration apparatus, means determining a maximum permissible speed,

means controlling the rate of deceleration from said maximum speed and a regulator therefor, adjusting means for the regulator, and means for setting the adjusting means correspondingly to a predetermined distance of train travel.

5. In train control apparatus of the type in which a permissible deceleration is determined by mechanism regulated responsive to distance of train travel, means determining the rate of deceleration of permissible speed therefrom, set-up apparatus for adjusting said means in advance of its actuation, and means for governing the set-up apparatus responsive to a distance of train travel.

6. A train control apparatus comprising a motor for normally maintaining the automatic brake control inoperative while its speed is high relatively to the train speed, but permitting the automatic brake apparatus to come into operation if it is low relatively to the train speed and a second motor which is controlled by the train movements to modify the action of the speed limiting motor.

7. A train control apparatus comprising an electric motor together with means for maintaining the automatic brake control inoperative while its speed is relatively high with respect to the train speed, but permitting the automatic application of the brakes when its speed is relatively low with respect to the train speed, a speed regulator in the circuit of said motor and actuated to establish a train deceleration speed curve as a maximum limit, a second motor operatively associated with the regulator to modify the deceleration curve and a regulator in the circuit of the second motor driven by the train.

8. A train control apparatus adapted to operate in the caution block to define a speed deceleration curve above which the engineer cannot drive his train without the automatic application of the brakes comprising an electric motor having a speed regulator in the circuit thereof and operated thereby to automatically and gradually slow up the motor from the maximum to a lower speed, means associated with said motor for maintaining the automatic brake control inoperative while the speed thereof bears a predetermined relation with reference to the speed of the train, but permitting said brake control apparatus to operate when the speed thereof is relatively lower than the speed of the train; a second motor operating on the aforesaid regulator and tending to oppose the slowing up of the first-named motor, and a second speed regulator for the circuit of the second motor which is directly driven by the train to gradually slow up the second motor, together with means for automatically adjusting the position of the

second regulator as the train moves along the track.

9. Apparatus for determining permissible train speeds including a motor, a regulator controlling it, a second motor, and means differentially responsive to the speeds of said motors for controlling said regulator.

10. In a train control apparatus, two motors, means whereby the speed of one may determine permissible train speed, a speed controller for said motor, and differential gearing operating said controller and under control of both of the motors.

11. Train control apparatus including a motor, circuits and connections tending to cause the motor to gradually reduce its own speed, a second motor, means for causing the second motor to oppose the action of the first motor as to its speed reduction, and controllable means for causing the second motor to reduce its speed and be brought to rest.

12. A train control apparatus comprising a three position relay adapted to be responsive to the track currents, an automatic brake valve magnet having its circuit completed through one position of said relay to maintain the automatic brake control circuit, an electric motor having a regulator in its circuit which is driven thereby to insert resistance and gradually slow up the speed of the same to zero, a pair of chaser contacts in the circuit of the brake valve magnet and forming an independent circuit when closed therefor, one of said contacts being driven by the motor and the other one being driven by a device actuated by the train in such a manner that when the speed of the motor is relatively higher than the train speed the contacts are closed to maintain the brake circuit, but when relatively low to interrupt the brake circuit, a second motor operating differentially upon the aforesaid rheostat to remove the resistance from the circuit, a second regulator in the circuit of the second motor which, in the inoperative position is in circuit with the second motor, means responsive to one position of the aforesaid relay to gear said second rheostat to the train axle to automatically cut out a portion of the resistance thereof upon entry into a caution block, and means operative when the relay goes to the third position for reversing the connections between the second regulator and the train axle to operate the same in the opposite direction, and simultaneously therewith energize both of said motors.

13. In train speed control apparatus, a motor whose speed determines permissible train speed, means cooperating therewith to tend to slow down and stop the motor, opposing means tending to maintain the speed of the motor, and a member moving with

the train to reduce and eliminate the effect of said opposing means.

14. In train speed control apparatus, a speed device tending to move at a rate independent of the train speed, its rate of movement determining permissible train speed, a second speed device for regulating the first speed device and means moved correspondingly with the train for regulating the second speed device.

15. A train control apparatus including a motor determining permissible train speeds, and mechanism operated by said motor to tend to reduce its own speed and bring it to rest.

16. A train control apparatus carried by the train and comprising an automatic brake application valve controlled by an electro-magnet whose circuit is normally completed by means adapted to be responsive to track currents to maintain the brakes released during clear track conditions, a pair of contacts forming an independent circuit for said electro-magnet, one of said contacts being driven directly from the train axle, the other of said contacts being driven by an electric motor, said contacts being closed when the motor is operating at a speed relatively higher than the speed of the train axle, but open when the relative speeds are reversed, and a controller in the circuit of said motor and driven directly thereby to gradually slow up the same from a maximum speed to zero speed together with means for energizing said motor and setting the same into operation.

17. A train control apparatus comprising an automatic brake control which is normally in the inoperative position, a motor adapted to be set into operation in a caution block and having means associated therewith for maintaining the normal position of the automatic brake control while its speed is relatively high with respect to the train speed, but compelling the brake application when the relative speeds are reversed, a controller for gradually slowing up said motor from its maximum speed along a predetermined deceleration speed curve and means adapted to be responsive to the track circuits to arrest the slowing up motion of said controller at a point along the deceleration curve and thereafter maintaining the speed of said motor constant throughout a predetermined track section.

18. A train control apparatus carried by the train and including an automatic brake valve magnet and a circuit therefor, a motor together with means associated therewith and with an element driven by the train axle for maintaining an independent circuit for said magnet while the speed of the motor is relatively high with respect to the speed of the train axle, but opening said independent circuit for the automatic ap-

plication of the brakes when the speeds are relatively reversed, a second motor, a controller for the first motor driven differentially from the two motors, the first motor tending to automatically slow itself up and the second motor tending to increase the speed of the first motor, a second controller for governing the maximum speed and the length of the deceleration curve of the second motor, said second controller being adapted to be driven in reverse directions by the train axle and means adapted to be responsive to track circuits for first setting the controller for the second motor and setting both motors into operation to define a decelerating speed curve for the train, and then at a predetermined point in the deceleration curve, arresting the motion of the second-named controller to thereby establish a constant speed operation of the two motors throughout a constant speed track section.

19. A train control apparatus comprising a motor and means associated therewith adapted to be responsive to a set up track section for defining a deceleration curve for the train, above which the engineer cannot drive his train on penalty of automatic brake application, and still further means associated therewith for arresting the deceleration of the motor at the beginning of the constant speed section and maintaining the speed thereof constant throughout.

20. Train control apparatus comprising switching mechanism adapted to be responsive to track circuit conditions, apparatus adapted to determine permissible train speeds including a regulating member therefor, means whereby the regulating member is moved in one direction when the switching mechanism is in one position to determine a decelerating speed, and means whereby the regulating member at another position of the switch mechanism may be moved in the other direction to adjust the apparatus preliminarily to determining a decelerating speed or may be held at a constant position to determine a constant speed.

21. In train control apparatus of the character described including a motor, speed regulator, means driven by the train for operating the regulator in one direction to set it up for functioning and in the other direction to function for regulating the apparatus for a determining decelerating speed, and means for holding it at a given position to regulate the apparatus to determine a constant speed.

22. In a train control apparatus including a motor whose speed may determine the permissible train speed, a regulating device therefor, means for operating said regulating device in either direction by the movement of the train, and means for holding it at rest when a constant train motor speed is desired.

23. In train control apparatus a switch mechanism adapted to be responsive to track circuit currents, a regulating member for train carried apparatus adapted to be adjusted by the train when the switch member is at a given position to an extent determined by the movement of the train, means for adjusting the regulating member in a reverse direction when the switch member is at another position, a switch controlled by a predetermined movement of the regulating member, and means controlled by said switch for causing said member to be thereafter non-adjustable while the switch member is at the first-named position.

24. In train control apparatus a regulating member therefor, gearing therefor, connected with gearing carried by the train, a magnet adapted to relatively reverse the movement of said gearing, another magnet adapted to disconnect the gearing to hold the regulating member at rest, and circuits and connections whereby at a predetermined position of said regulating member the one or other magnet only may be energized.

25. In train control apparatus, means for determining a permissible train-speed deceleration, and a regulator for varying the rate of deceleration to be determined thereby, set-up or adjusting means for the regulator, and relay apparatus having one position establishing a circuit to actuate the set-up apparatus, and another position establishing a circuit to actuate the deceleration apparatus with its regulator thus set-up.

26. In a train control apparatus, a relay apparatus adapted to be responsive to currents along the track to complete either of three circuits, a train control device with connections to include it as a part of each of the three circuits, speed control apparatus in one of the circuits connected to control the energization of the train control device, and set up apparatus for regulating the action of the speed control apparatus to adjust it for a desired rate of permissible deceleration in the third of said circuits.

27. In a train control system, permissible train speed apparatus including a member whose movement in one direction regulates for deceleration and at rest regulates for maintained constant speed, means for causing the train to move said member correspondingly with the train movement to an initial position to control the length of the deceleration distance and means for causing the said member to be maintained at a given position to regulate for a constant speed limit.

28. In train control apparatus, permissible train speed apparatus, a regulator therefor and means for controlling the regulator responsively to the movement of the train to cause it to regulate the rate of deceleration from a given maximum permis-

sible speed and also responsively to the movement of the train to adjust it and thereby determine the rate of deceleration.

29. In a train control system, permissible train speed apparatus, means tending to control the same to set up a given decelerating curve and means acting simultaneously to oppose the setting up of a decelerating curve, and a regulating member acting to control the relative effect of said opposing means and itself controllable by the movement of the train.

30. The apparatus specified in claim 29 wherein the regulating member is controlled to be moved by the train in one direction for regulating the opposing means and to be moved in the opposite direction for setting up a standard for subsequent regulation.

31. In a train control system, permissible train speed apparatus including means acting independently of train movement and tending to set up a deceleration curve for such apparatus and cooperating means controlled by the movement of the train to produce a resultant deceleration curve.

32. The combination specified in claim 31 wherein the said cooperating means includes a movable regulating member and means controlled by train movement to adjust its position to set up a standard for subsequent regulation.

33. In train control apparatus, a permissible speed control mechanism, a regulating member therefor whose position determines the permissible speed that may be maintained, means for moving the regulating member from the train in either direction or for maintaining it at any definite position, and electro-responsive devices controlling the operation of said moving and maintaining means.

34. In train control apparatus, a permissible speed control mechanism, a regulating member therefor whose position determines the permissible speed that may be maintained, relay apparatus adapted to be operated by currents along the track, electro-responsive apparatus adapted to connect said member to be operated by the train, other electro-responsive apparatus adapted to maintain said member stationary, a circuit closed by said relay apparatus to one or other electro-responsive apparatus according to the position of said regulating member, and means for causing the regulating member to be moved by the train in the opposite direction to a normal position when neither electro-responsive apparatus is energized.

35. In a train control device switching mechanism, permissible speed apparatus connected to operate to control said train device at one position of the switching mechanism, a regulating member for the permissible speed apparatus, electro-responsive ap-

paratus to gear said member to the train to be moved correspondingly with the train, and a circuit to said electro-responsive device closed at another position of the switching mechanism.

36. Permissible train speed deceleration apparatus including a moving contact whose rate of movement determines the deceleration of the train, means tending to decelerate said contact along a given curve, means tending to oppose such deceleration, and means whereby the train's movement gradually lessens and eliminates the action of said opposing means, whereby a deceleration curve

is produced which is a lengthening and modification of said first deceleration curve.

37. Apparatus as specified in claim 36 where means are provided operated by the movement of the train to preliminarily adjust the said opposing means to fix its degree of opposition at the commencement of the decelerating period and the distance of train movement necessary to eliminate such opposition.

In testimony whereof, I have signed my name to this specification.

OSCAR S. FIELD.
